ARTICLE OF FURNITURE

Bertis F. Hamilton, deceased, late of Columbus, Ind., by William S. Hamilton, executor, Earl F. Hamilton and William S. Hamilton, Columbus, Ind., assignors to Hamilton Manufacturing Corporation, Columbus, Ind., a corporation of Indiana

Filed July 31, 1956, Ser. No. 601,188

8 Claims. (Cl. 155—112)

This invention relates to furniture, more especially chairs, settees, sofas, and the like, and is particularly concerned with an article having a frame structure which lends itself to construction from metal tubing. It is an object of the invention to produce an article of furniture having a tubular-metal frame which can be shipped in knocked-down condition in a compact package and easily erected. Another object of the invention is to produce an article of knocked-down furniture which, when erected, will be sturdy and rigid.

An article of furniture embodying the invention possesses a generally rectangular seat-frame formed of metal tubing and including end elements which, at the rear of the seat, are bent to extend upwardly for a short distance. A back-frame, also desirably formed of metal tubing, has end elements the lower ends of which are adapted to be telescopically associated with the up-bent end elements of the seat frame. The back frame may also include a bottom element having bent ends which lap the aforesaid telescopically associated elements and which are secured to both of them to effect attachment of the back frame to the seat frame. Side members, each desirably formed of a length of metal tubing bent into a general inverted U-shape, provide seat-frame supports and also supports for arm rests. Slats extending across the seat frame from front to back provide support for a seat cushion, while slats extending generally vertically across the back frame provide support for a back cushion.

Other objects and features of the invention will become apparent from the further description and the accompanying drawings in which:

Fig. 1 is a perspective view of an erected sofa frame;

Fig. 2 is a vertical section on the line 2—2 of Fig. 1;

Fig. 3 is a fragmental plan view illustrating one end of the seat frame and the associated side member;

Fig. 4 is a section on the line 4—4 of Fig. 3;

Fig. 5 is a fragmental plan view, on an enlarged scale, illustrating a preferred form of means for use in interconnecting the seat frame and side members;

Fig. 6 is a generally vertical section on the line 6—6 of Fig. 5;

Fig. 7 is a detailed view, in partial section, illustrating the connection between the seat and back frames;

Fig. 8 is a fragmental view illustrating further details of construction; and

Fig. 9 is a vertical section on the line 9—9 of Fig. 1.

The sofa illustrated in the drawings comprises a seat frame designated in its entirety by the reference numeral 10. As shown, the frame 10 includes a front member 11 of metal tubing bent to provide rearwardly extending end stretches 12. The seat frame also includes a rear member 13, likewise desirably formed of metal tubing, and having flattened ends 13' (Fig. 3) received in slots in the inner faces of the end stretches 12. Such end stretches 12 continue rearwardly beyond the rear member 13, where their ends are bent upwardly as indicated at 15 for a purpose which will become apparent hereinafter.

2

The back frame, designated in its entirety by the reference numeral 20, includes an upper member 21 of metal tubing bent into a general U-shape to provide downwardly extending end stretches 22. At its lower end, each of the end stretches 22 receives a pilot 23 which projects beyond such end stretch for reception in the associated up-bent end 15 of the seat frame. The back frame also includes a lower member 25, conveniently of metal tubing, the ends 26 of which are bent upwardly, collapsed, and shaped in cross-section to conform to the tubing of which the elements 15 and 22 are formed. As will be clear from Fig. 7, the up-bent ends 26 of the lower member 25 overlap the joint between the elements 15 and 22, and are bolted to the elements 22 by bolts 27 and to the elements 15 by bolts 28 to secure the seat and back frames together.

The seat is supported from the floor by two side members each desirably formed as a length of metal tubing bent into a general inverted U-shape to provide an upper stretch 30, a front leg 31 and a rear leg 32. Feet 33 may be mounted in any convenient manner at the lower ends of the front and rear legs. The legs, which lie outwardly beyond the end elements 12 of the seat frames, are conveniently releasably secured thereto through the medium of brackets 35 (Figs. 5 and 6). Each of these brackets is desirably formed as a drawn sheet-metal stamping shaped to provide intermediately a saddle portion 36 adapted to fit against the side of the associated leg and end portions 37, including flanges 38, which conform to the cross-sectional curvature of the tubing from which the front seat-member is formed. The brackets 35 are secured to the end elements 12 of the seat-frame at appropriate locations, as by welding or brazing. At the location of each bracket, the associated leg 31 or 32 is provided internally with a nut 40 adapted to receive a screw 41 passing through holes in the end element 12 and in the saddle 36. The latter hole is large enough to receive any portion of the nut 40 located exteriorly of the leg, in order that the leg may seat firmly against the saddle 36.

The upper stretch 30 of each side member supports an arm including an inverted sheet-metal pan 43 covered on its top and sides with appropriate upholstery material 44. The arm is secured to the intermediate stretch 30 of the associated side member by screws 45 which pass upwardly through the stretch 30 and into the sheet-metal pan 43. To relieve the screws 45 of stresses incident to the application of any force which would tend to rock the arm about the axis of the stretch 30, the latter is desirably given the sinusoidal form illustrated in Fig. 3, so that it provides support for the pan 43 at points spaced transversely of the stretch 30.

For the purpose of providing support for a seat cushion or cushions, slats 47 of resilient sheet-metal extend between the front and rear seat-frame members 11 and 13. To connect the slats to the seat-frame members, the latter are provided at intervals along their inner faces with slots receiving the ends of the slats; and at their ends, the slats are bent downwardly to provide the ears 48 shown in Fig. 4.

In assembling the seat, the ears 48 are passed through the slots in the members 11 and 13 before the member 13 is secured to the end stretches 12 of the member 11; and, after the slat-ends 48 are in place in the front and rear members 11 and 13, the end stretches 12 are then sprung outwardly to permit the flattened ends 13' of the rear member to be inserted into the slots in the inner faces of the end stretches 12 to secure the front and rear seat-frame members together. In this condition, the end stretches 12 desirably bear resiliently against the shoulders formed on the rear member 13 as an incident to formation of the tongues 13'.

To provide support for a back cushion or cushions 50 (Fig. 2) the back frame includes slats 51' the ends of which are received in slots in the upper and lower back-frame members 21 and 25. In order to provide greater seating-depth, the ends 52 of each back-slat 51 may be desirably offset forwardly with respect to the body of the slat, as shown in Fig. 9. For the purpose of opposing forward creeping of the seat cushion, the body portion of each of the slats 47 may be offset downwardly relative to the end portions thereof. Preferably (see Fig. 4), this offsetting is greatest at the front end of each slat to provide, just rearwardly from the front seat member 11, a rearwardly presented shoulder 53.

Depending on the length of the article, it may be desirable to provide an additional connection between the seat frame and back frame intermediate the ends thereof, and it may also be desirable to provide an additional and intermediate floor support for the seat. I have therefore shown in the drawings an auxiliary back member 56 which is desirably of metal tubing and which extends across the back frame between the upper and lower members 21 and 25 thereof and is secured to the seat frame. To connect the auxiliary member 56 with the upper member 21, the upper end of the auxiliary member is flattened to provide a tongue 57 which enters a slot in the tubular top member 21. Desirably, the tongue 57 is bent rearwardly as indicated in Fig. 2 to prevent relative upward movement of the top member 21 of the back frame.

Where the auxiliary member 56 crosses the lower back-frame member 25, the latter may be partially collapsed as indicated at 58 in Fig. 8, to permit the two members to be located more nearly in the same plane and also to provide a groove which locates the auxiliary member 56 longitudinally of the lower member 25. The member 56 is provided with a nut 60 which receives a screw 61 extending through the lower member 25 to hold the two members together.

The member 56 continues downwardly and forwardly beyond the member 25 to a position beneath the rear member 13 of the seat frame 10, to which it is secured as by a bolt 62. Where the seat frame is to be provided with an intermediate support, the auxiliary member 56 may continue forwardly, as indicated at 64, below the seat frame 10 and be connected to the front member 11 thereof. To effect this connection, the front end of the extension 64 is shown as flattened to provide a tongue 65 received in a slot of the inner wall of the front seat-frame member 11, such tongue being desirably bent downwardly as shown in Fig. 2. The intermediate portion of the extension 64 is depressed, as indicated, to prevent interference with downward deflection of the slats 47 and seat cushions under load, and an intermediate seat-supporting member 66 is associated with it. Desirably, the intermediate seat-supporting member is formed of metal tubing with an intermediate portion lying directly below and conforming to the extension 64 and with front and rear legs 67 and 68, which may be provided with feet 33. Conveniently, the extension 64 and the intermediate seat-support 66 are secured together by brazing or welding.

An article constructed as above described lends itself to shipment in knocked-down condition and to ready erection. In knocked-down condition the seat frame 10 with its rear member 13 and slats 47, the back frame 20 with its slats 51 and lower member 25, the side members, and the auxiliary member 56 are separate units. The intermediate seat-support 66, when provided, forms part of a single unit with the auxiliary member 56. Except for the up-turned ends 15 of the seat frame and for the sinusoidal form of the upper stretches 30 of the side members all these units are essentially flat and can be packed in superposed relation in relatively small space.

Erection of the article shown is perhaps most conveniently effected by first engaging the tongue 65 of the auxiliary member 56—64 in the slot in the front seat-frame member 11 and then securing one of the side mem-

bers to the seat frame with the bolts 41. If, as in the article shown, the auxiliary member 56 includes the forwardly extending stretch 64 to which the intermediate support 66 is secured, the tongue 65 is next inserted through the slot in the front seat-frame member 11 and the bolt 62 applied connecting the intermediate support to the rear seat-frame member 13. The back frame is then lowered in front of the member 56 until the tongue 57 enters the slot in the upper back-frame member 21, and the pilots 23 are inserted into the upwardly bent rear ends 15 of the seat frame. The pilots 23, in the plane of the back frame, have a slight clearance, indicated exaggeratedly at 70 in Fig. 7, with the walls of the tube-ends 15 to facilitate their insertion, one at a time and with any necessary springing of the back frame, into such tube-ends while the back frame remains connected to the auxiliary member 56 at 57. After insertion of the pilots 23 into the tube-ends 15, the other side member is secured to the seat frame, and the bolts 28 are inserted and tightened to secure the ends of the back frame and seat frame together. Finally, the screws 61 and 62 are applied to secure the members 13 and 25 to the auxiliary member 56—64.

We claim as our invention:

1. In a settee or the like, a generally rectangular seat frame formed from metal tubing and having front, rear, and end members, legs supporting said seat frame, a back frame formed from metal tubing and having top, bottom, and end members, the end members of the seat frame extending rearwardly past said rear member and being bent to project generally upwardly, means providing telescoping joints between said up-bent ends and the end members of the back frame, said bottom member having transversely projecting ends extending along the end members of the back frame and the up-bent ends of the end members of the seat frame, means connecting the projecting ends of said bottom member to the end members of both the seat and back frame, a plurality of cushion-supporting slats on said seat and back frames.

2. The invention of claim 1 with the addition of an auxiliary frame member extending across said back frame intermediate the ends thereof and into proximity to said rear member and secured to said top, bottom, and rear members.

3. The invention of claim 2 with the addition that said top member is of metal tubing having a slot in its wall, said auxiliary member having an upper end which extends through said slot into the interior of the tubular top member and is formed to provide a laterally projecting tongue preventing upward movement of said top member relative to said auxiliary member.

4. The invention of claim 2 with the addition that said auxiliary member extends forwardly beneath said rear member and is connected to said front member, said auxiliary member being provided below the seat frame with legs adapted to engage a floor or other supporting surface.

5. The invention of claim 2 with the addition that said auxiliary member extends forwardly beneath said rear member to said front member, said front member having a slot in its wall, and said auxiliary member having at its front end a tongue projecting through such slot into the interior of the front member.

6. In a chair, settee, or the like, a generally rectangular seat frame having front, rear, and end members, a back frame having top, bottom, and end members, a plurality of slats on said seat and back frames for supporting cushions thereon, a chair-supporting side member at each lateral end of the chair, each of said side members having an upper horizontal tubular stretch provided with at least two offsets in a plane normal to the plane of their associated side member, an arm mounted on each of said side members and having an inverted metal pan connected to and supported on the upper faces of the 75 horizontal stretch and offsets on said side member, the

distance between a pair of adjacent offsets being greater than the width of one of the arm pans with said horizontal stretches and the offsets thereon abutting the opposed depending lateral edges of said arm pans mounted thereon to prevent lateral rocking movement of the arms on the side members.

7. In a chair, settee, or the like, a generally rectangular seat frame having tubular front, rear and end members and a first set of downwardly offset slats extending between said front and rear members, said front and rear members having slots in their mutually opposed walls, said slats being formed of metal and extending through said slots with the ends of each of said slats being bent to provide vertically projecting ears located within the front and rear members and normally disposed in spaced relation from the inwardly presented walls of the tubing forming said front and rear members to permit limited fore-and-aft sliding movement of the ends of said slats within the front and rear members of the seat frame without withdrawal of the slat ends therefrom, a back frame interconnected to the seat frame and having end members and top and bottom members interconnected by a second set of slats, means interconnecting said back and seat frame, and a plurality of ground-engageable legs supporting said seat and back frames.

8. In a chair, settee, or the like, a generally rectangular seat frame having tubular front, rear and end members, a first set of slats having their ends received in slots formed in the mutually opposed inner walls of said front and rear members, said slats being formed of metal and having their ends bent to form vertically projecting ears located within said front and rear members in normally spaced relation to the inwardly presented walls of said front and rear members to permit limited fore-and-aft sliding movement of the ends of the slats without withdrawal of the slat ends from the front and rear members of the seat frame, a back frame interconnected to said

seat frame and having end members and top and bottom members interconnected by a second set of slats, a chair-supporting member at each lateral end of the chair, each of said chair-supporting members having an upper horizontal tubular stretch provided with at least two offsets in a plane normal to the plane of their associated chair-supporting member, and an arm mounted on each of said chair-supporting members and having an inverted metal pan connected to and supported on the upper faces of the horizontal stretch and offsets on said chair-supporting member, the distance between a pair of adjacent offsets being greater than the width of one of the arm pans with said horizontal stretches and the offsets thereon abutting the opposed depending lateral edges of said arm pans mounted thereon to prevent lateral rocking movement of the arms on the chair-supporting members.
